UNITED STATES PATENT OFFICE.

JOHN L. FAY, OF ST. LOUIS, MISSOURI.

COMBINED CHOKE-COIL AND FUSE.

1,187,894.

Specification of Letters Patent. Patented June 20, 1916.

Application filed October 19, 1914. Serial No. 867,349.

To all whom it may concern:

Be it known that I, JOHN L. FAY, a citizen of the United States, residing at the city of St. Louis, State of Missouri, have 5 invented a certain new and useful Improvement in Combined Choke-Coils and Fuses, of which the following is a full, clear, and exact description, such as will enable others skilled in the art to which it appertains to 10 make and use the same, reference being had to the accompanying drawings, forming part of this specification, in which—

Figure 1 is a vertical section taken through the center of a combined choke coil and fuse 15 of my improved construction. Fig. 2 is a horizontal section taken approximately on the line 2—2 of Fig. 1. Fig. 3 is a view looking against the bottom of the housing or shell of the device and showing the re- 20 movable member in horizontal section. Fig. 4 is an enlarged detail section taken approximately on the line 4—4 of Fig. 3.

My invention relates to a combination 25 fuse and choke coil, the principal object of my invention being to combine in one element a choke coil and a fuse, and which device is particularly intended for the protection of transformers in transmission lines or distribution circuits.

30 It will be understood that when, during a storm accompanied by lightning, the induced discharge encounters an inertia or inductance, a very great electro-motive force is created between the terminals of the par- 35 ticular portion of the circuit which is im- mediately adjacent to the lightning dis- charge. Thus, a sudden rush of current com- ing in over a transmission line or distribu- 40 tion circuit encounters the highly inductive windings of wire in the transformer located in said circuit.

The inductance of the windings in the 45 transformers dams or chokes the rush of current, which action very frequently causes a break-down of the primary and secondary windings or effects a ground to the trans- 50 former case, and which result is caused by the built-up rise in voltage produced by high frequencies resulting from a lightning stroke or by induced charge of high fre- 55 quency from an adjacent lightning stroke. As a result, the transformer is destroyed and the secondary circuit to which the consumers are connected is rendered unserviceable, and this necessitates expensive repairs be- sides loss of service to consumers.

It is the present practice to utilize in the connection from the transformer to the primary system of wires a device known as a primary fuse block or fuse cut-out, which 60 device is generally made of porcelain in which is located a fuse wire. This fuse wire melts when it receives current in excess of its rated capacity. Under this practice, when the coils of a transformer are punc- 65 tured by a lightning discharge, it permits of a rush of current to flow, due to short circuited coils. This excessive rush of current causes the fuse to melt in the primary cut- 70 out, and such action very frequently results in the destruction of said primary cut-out by reason of the high temperatures pro- 75 duced from the sustained arc through the gaseous vapors.

It is the purpose of my invention to over- 80 come the undesirable results just referred to, and to provide a comparatively simple, in- 85 inexpensive and easily applied device which combines a choke coil with a fuse, which not only protects a transformer as a fuse device, 90 but dams or chokes the rush of current pro- 95 duced from lightning, thereby producing a rise in potential on the lightning arrester side of the line that compels the lightning arrester to act in the manner intended.

With the foregoing and other objects in 90 view, my invention consists in certain novel features of construction and arrangement of parts, hereinafter more fully described and claimed.

Referring by numerals to the accompany- 95 ing drawings, 10 designates the housing or shell which receives the plug or member which carries the choke coil and fuse, said housing being preferably constructed of glass or porcelain and of hollow cylindrical shape and having its upper end closed. The lower open end of this shell or housing is provided with an integral depending flange or apron 11. Formed through this apron and on opposite sides thereof are inclined apertures 12 through which pass the terminals of a line or circuit, and the ends of these terminals are connected in any suitable manner to pairs of contact plates 13, the same being fixed to the shell or housing on the shoulder between the body thereof and the apron 11.

The removable member which carries the 100 choke coil and fuse is formed of suitable 105 insulating material such as fiber, porcelain or analogous material, and it consists of a 110

main body portion 14 and a handle portion 15. Both body and handle portions are cylindrical in form and formed integral therewith at a point between the body and handle is an outwardly projecting flange 16 which serves to protect the hand of the operator while the detachable member is being placed in or removed from position within the housing or shell. A corresponding protecting flange 17 is formed integral with the lower end of the handle portion 15. Formed through the body and handle portions is an axially disposed bore or passage way 18 and located in the upper portion of this bore or passage way is a tubular lining 19 of fire-proof insulating material such as asbestos, transite or analogous material. Formed in the surface of the body 14 is a spirally disposed groove 20 in which is located a section of wire 21 which serves as the choke coil of the device. The lower end of this section or coil of wire is connected to a bracket 22 which is fixed to and projects outwardly from the lower portion of the body 14, and said bracket is adapted to engage between a pair of the contact plates 13. The upper end of the body 14 is tapered or made conical as shown in Fig. 1, and the upper end of the coil 21 is connected to a contact plate 23, which latter is fixed to the tapered upper end of said body. A fuse wire 24 extends through the upper portion of the tubular lining 19 and the upper end of said fuse is fixed in any suitable manner to the contact plate 23. The lower portion of said fuse is threaded through an inclined bore or passage way 25 which is formed in the lower portion of the body 14 and the lining 19. The lower end of this bore or passage way terminates adjacent to the flange 16 and the end of the fuse which projects from said lower end is attached in any suitable manner to an outwardly projecting bracket 26, the same being oppositely disposed with respect to the bracket 22, and said bracket 26 is adapted to engage between a pair of the contact plates 13. Positioned on the conical or tapered upper end of the body 14 is a conical cap 27, the same serving to close the upper end of the bore or passage way through the body 14 and also to cover the contact plate 23. Fixed in any suitable manner to the side of the housing 10 is an outwardly projecting bracket 28, and fixed thereto is an inverted L-shaped member 29, the horizontal leg of which is slotted as designated by 30. The horizontal leg of a second inverted L-shaped member 31 overlies the horizontal leg of said member 29 and passing through a slot 32 formed in the horizontal leg of said member 31 and through the slot 30 is a bolt 33, the lower end of which receives a nut 34. The members 29 and 31 are adapted to engage a cross arm, thereby sup-

porting the housing and the member carrying the fuse and choke coil in proper position. By making the member 31 adjustable with respect to the member 29 the support can be applied to cross arms of various widths. 70

When the removable member carrying the choke coil and fuse is to be positioned in the housing, the operator grasps the handle portion 15 of said removable member and the wide flanges 16 and 17 serve to protect the hand against contact with the plates 13 or from an accidental blow-out of the fuse resulting from short circuit while the device is being assembled. The body portion 14 is now moved upwardly into the housing 10 until the brackets 22 and 26 strike against the shoulder between the body of the housing and the apron 11. The operator now partially rotates the removable member so as to position the brackets 22 and 26 between the pairs of contact plates 13 and thus the fuse and choke coil are brought into circuit with the terminals of the line which are connected to the pairs of plates 13. In case the fuse blows out the melted metal and gases resulting from such blow-out will discharge downwardly through the opening in the tubular lining 19, and through the opening 18 inasmuch as this discharge is prevented from finding exit through the upper end of the detachable member by the cap 27 which, as heretofore stated, closes the opening at the upper end of said removable member. 90

It will be understood that the size of the choke coil and the size of the wire of which said coil is formed may vary to meet the requirements of various voltages and frequencies. For illustration, a choke coil three inches long, one inch in diameter and comprising ten turns of #10 copper wire will produce a potential of .00063 volts at a normal full load current of 20 amperes at 60 cycles. The frequency of the average lightning discharge may safely be said to be of many thousands cycles and as the potential across a reactance varies directly with the frequency it will be understood that under such conditions a potential of several hundred volts will be produced across the terminals of a coil of approximately the dimensions just mentioned and as a result the inductive windings of the transformer adjacent to the coil will be protected inasmuch as the built-up lightning discharge is forced to flow across the air or spark gap of the adjacent lightning arrester. The coil also has the effect of damming or choking the rush of current, thereby preventing strain on the transformer windings, reducing break-down of transformer insulation and the interruption of service to the consumers. The use of such a coil also prevents damage to primary fuse blocks inasmuch as the arc 130

is reduced and likewise the effects of a sustained arc is reduced.

It will be understood that my improved device is located on a suitable support or cross arm adjacent to a transformer or other apparatus and when so positioned the transformer or apparatus is effectively protected against sudden rushes of current which may come in on the line as a result of lightning discharge. When the removable member of the device is positioned in the housing 10 the flange 16 practically forms a closure for the lower end of said housing, and thus the choke coil, fuse and contact plates are effectively protected against rain, snow and ice and when it becomes necessary to replace a blown out fuse the removable member can be readily detached and a new fuse placed in position by removing the cap 17 and threading the fuse wire through the inclined passage way 25 and the passage way through the center of the lining 19.

A device of my improved construction is comparatively simple, can be easily and cheaply manufactured, and forms an efficient protection for transformers and like devices against abnormal and destructive currents coming in over a transmission line or distribution circuit.

It will be readily understood that minor changes, in the size, form and construction of the various parts of my improved choke coil and fuse can be made and substituted for those herein shown and described, without departing from the spirit of my invention, the scope of which is set forth in the appended claims.

I claim:

1. In a device of the class described, the combination with a housing provided with contacts with which the terminals of a circuit are connected, of a tubular member removably positioned within said housing, the upper end of said member being closed and its lower end open, attaching members on said removable member for engaging the contacts on the housing, a choke coil on the removable member, which choke coil is connected to one of the attaching members, a fuse connected to said choke coil and passing partially through the tubular member, which fuse is connected to the other of the attaching devices of said removable member, a tubular handle depending from the tubular member, a flange between said tubular member and tubular handle, and a flange at the lower end of said tubular handle.

2. In a device of the class described, the combination with a housing having contacts, of a tubular member removably positioned in said housing, attaching devices on said tubular member which are adapted to engage the contacts on the housing, a choke coil wound upon the outer face of said tubular member, one end of which

choke coil is connected to one of the attaching devices, a fuse extending through said tubular member and connected near the upper end thereof to the choke coil, the lower end of said fuse being connected to the other 70 one of the attaching devices, a comparatively wide horizontally disposed flange at the lower end of the tubular member, a tubular handle depending from the tubular member, a comparatively wide flange at the 75 lower end of said tubular handle, and a cap removably positioned on the upper end of the tubular member and closing the opening therethrough.

3. In a device of the class described, the combination with a housing provided with contacts with which the terminals of a circuit are connected, of a tubular member removably positioned within said housing, attaching devices on said removable member 85 for engaging the contacts on the housing, a choke coil wound upon said tubular member, one end of which choke coil is connected to one of the attaching devices, a fuse extending partially through the tubular 90 member, and connected near the upper end thereof to the choke coil, the lower end of said fuse being connected to the other one of the attaching devices, and a cap removably positioned on the upper end of the 95 tubular member and normally closing the opening therethrough.

4. In a device of the class described, the combination with a housing provided with contacts with which the terminals of a circuit are connected, of a tubular member removably positioned within said housing, attaching devices on said removable member for engaging the contacts on the housing, a choke coil wound upon the outer face of 105 said tubular member, one end of which choke coil is connected to one of the attaching devices, a fuse extending partially through the tubular member and connected near the upper end thereof to the choke 110 coil, the lower end of said fuse being connected to the other one of the attaching devices, a cap removably positioned on the upper end of the tubular member and normally closing the opening therethrough, 115 and a tubular handle depending from said tubular member.

5. In a device of the class described, the combination with a housing having contacts to which the terminals of a line are connected, of a tubular member removably positioned in said housing, attaching devices on said member which are adapted to engage the contacts on the housing, a choke coil wound upon the outer face of said tubular member, one end of which choke coil is connected to one of the attaching devices, a fuse extending partially through the tubular member, there being an inclined aperture formed through the wall of the tubular 125 130

member through which the lower portion of the fuse passes, the lower end of said fuse being connected to the other one of the attaching devices, and the upper end of said fuse being connected at the top of the tubular member to the choke coil.

6. In a device of the class described, the combination with a housing having contacts to which the terminals of a line are connected, of a tubular member removably positioned in said housing, attaching devices on said member which are adapted to engage the contacts on the housing, a choke coil wound upon the outer face of said tubular member, one end of which choke coil is connected to one of the attaching devices, a fuse extending partially through the tubular member, there being an inclined aper-

ture formed through the wall of the tubular member through which the lower portion of the fuse passes, the lower end of said fuse being connected to the other one of the attaching devices and the upper end of said fuse being connected at the top of the tubular member to the choke coil, and a cap removably positioned on the upper end of the tubular member for closing the opening therethrough.

In testimony whereof I hereunto affix my signature in the presence of two witnesses, this 17th day of October, 1914.

JOHN L. FAY.
